UNITED STATES PATENT OFFICE

FREDERICK C. BARGAR, OF COLUMBUS, OHIO, ASSIGNOR TO PINES WINTERFRONT COMPANY, OF CHICAGO, ILLINOIS, A CORPORATION OF DELAWARE

SHUTTER CONTROL FOR INTERNAL COMBUSTION ENGINES

Application filed March 29, 1929. Serial No. 351,002.

The present invention relates to shutter controls, and is particularly concerned with shutter controls for radiators or enclosures of internal combustion engines.

- 5 It is highly desirable that the shutters for controlling the flow of cooling fluid about an internal combustion engine be closed as soon as the engine stops, to preserve all of the heat possible in the engine, and it is also desirable 55
 10 that the cooling apparatus be inoperative until the engine has reached a predetermined operating temperature, after which the shutters must be opened to prevent overheating of the engine. 60
 15 The present invention contemplates the accomplishment of the foregoing results automatically by the use of means for actuating the shutters responsive to the running condition of the motor, and thermal means for controlling said actuating means at a predetermined temperature. 65

One of the objects of the invention is the provision of a shutter control adapted to close immediately upon the stopping of the engine and adapted to be opened only when the engine is running and has simultaneously reached a predetermined temperature.

Another object is the provision of a shutter control provided with a positive actuating device adapted to be controlled by a thermally responsive device at a temperature which may be predetermined with a high degree of accuracy.

Another object is the provision of a thermal control for shutters which is responsive to a certain predetermined temperature without variations due to wear, adjustment of parts, or change in the characteristics of the thermal device.

40 Another object is the provision of a thermal control which is also responsive to the running condition of the motor, and which includes means released by the melting of a solid for controlling the actuating device for the shutters.

Another object is the provision of a novel latching mechanism for devices which are actuated responsive to the melting of a solid, which latching mechanism is adapted to return to its initial position after releasing the

controlled device, so that the parts will be in proper position when the thermally responsive element becomes solid again.

Another object is the provision of a shutter control of the class described which is adaptable alike for use directly upon the motor block in engines having an air cooling system, or upon the radiator if desired, where a water cooling system is used. 55

Other objects and advantages of the invention will be apparent from the following description and from the accompanying drawings in which similar characters of reference indicate similar parts throughout the several views. 60

Referring to the drawings of which there are two sheets:

Fig. 1 is a diagrammatic view in elevation showing the invention applied to an internal combustion engine, having a water cooling system; 70

Fig. 2 is a medial sectional view taken through the controlling device of Fig. 1, with the parts in the position corresponding to the position when the engine is cold and not running; 75

Fig. 3 is a view similar to Fig. 2 with the parts of the controlling device in the act of being released at a predetermined temperature; 80

Fig. 4 is a view similar to Fig. 2 with the parts in the position which they may assume when the engine is running, having already reached a predetermined temperature so that the shutters are open; 85

Fig. 5 is a sectional view of a modified form of mounting for the device;

Fig. 6 is a view in perspective of the pawl used on the latching device;

Fig. 7 is a side view of the plunger or movable element which is latched by the pawl of Fig. 6. 90

Referring to Fig. 1, the device in the present invention is here shown in conjunction with an internal combustion engine 10, having an oil sump 11, a fan 12, and a water cooling radiator 13. It should be understood, however, that the invention may be used as well with engines employing air cooling systems, in which case, the shutters 14 are 100

adapted to control the flow of air about the internal combustion engine 10, which is surrounded by the enclosure diagrammatically shown at 15.

- 5 The shutters may be of any conventional construction, including built-in or detachable shutters comprising a frame 16 and a plurality of sheet metal shutters 14, having backwardly extending arms or flanges 17 at 10 their ends for pivotally mounting the shutters in frame 16.

At one end of the shutters 14, the arms 17 may be connected by a shutter bar 18, which is pivotally secured to each of the arms 17 and 15 adapted to simultaneously actuate a plurality of shutters. The shutters are preferably urged to closed position by a coil spring 19 having one end secured to the shutter bar 18 and the other end secured to the frame 16. 20 The frame 16 may be provided with a bell crank 20 pivotally mounted thereon and having a pin and slot connection to the shutter bar 18, and the bell crank 20 may be connected by means of a connecting rod 21, having 25 a turnbuckle 22, to a bell crank 23 carried by the shutter actuating device.

The present invention preferably includes a pressure responsive device 24 adapted to actuate the shutters 14 to open position, responsive to the running of the engine 10, and the pressure responsive device 24 is preferably connected by a conduit 25 to the oil pump shown diagrammatically at 26. The pressure generated by the oil pump 26 is substantially constant and does not fluctuate with the different positions of the throttle, as is the case where pressure devices are actuated by suction from the intake manifold of the engine.

40 The pressure responsive device 24 is also provided with means for rendering the same inoperative until the engine has reached a predetermined temperature, so that the shutters will remain closed to bring the engine to 45 proper operating temperature in the shortest possible time. In order to more accurately predetermine the temperature at which the shutters 14 will be actuated, I prefer to use a thermally responsive solid 27, which is 50 adapted to melt at a predetermined temperature for releasing the pressure responsive device 24 and controlling the shutters.

The melting temperature of a metallic solid is a characteristic which is always substantially the same, and consequently, the present shutter control which depends upon the melting of the solid 27 will always be actuated at an accurately predetermined temperature. The temperature at which the solid 27 will melt depends upon its composition and it will be understood by those skilled in the art that the percentages of lead, zinc, and other elements employed in the composition will determine the melting temperature. As the proper composition of a solid

having the characteristics desired may be readily ascertained from tables which give the melting points of alloys, no specific composition need be disclosed here, but it is sufficient to say that the solid 27 should preferably be so constituted that it will melt at about the most efficient operating temperature of the engine. The device is thus adapted to maintain the shutters closed until the engine is brought up to the proper operating temperature, at which time the shutters are opened and the cooling apparatus of the engine becomes effective.

70 The shutter control device indicated in its entirety at 28 may be attached to the engine block or it may be attached to a part of the radiator 13, but in either case, it is adapted to be heated by the heat derived from the engine. The control device 28 is preferably attached to the engine block so as to more 75 closely follow the temperature conditions within the engine 10, most of the heat being transmitted to the solid 27 by conduction through the metallic parts of the engine and control device.

79 The control device may consist of a casing 29 having a pressure chamber 30 which is open at one end 31 and adapted to be closed by the pressure responsive device or bellows 24. The casing 29 is provided with an annular cover flange 32 and the sylphon 24 may be provided with an annular attaching flange 33 adapted to be clamped between the cover 34 and the cover flange 32 by the screw bolts 35, threaded into the cover flange 32. The bellows 24 comprises an expansible sheet metal member of conventional form, for which an ordinary diaphragm may be substituted, if desired. The lower end 35 of the bellows 24 may be closed by an end plate 36 welded or otherwise secured thereto and adapted to support a plunger or shutter actuating member 37.

85 The cover 34 may comprise a cast metal member formed with an attaching flange 38 and with an annular guide member 39 surrounding a central aperture 40. The cover 34 is also provided with an upwardly projecting lug 41 for pivotally supporting the bell crank 23 by means of a rivet 42, and the bell crank 23 is provided with an arm 43 having a curved surface 44 for pivotally and slidably engaging the outer end 45 of the plunger 37. The opposite arm 46 of bell crank 23 is provided with an aperture 47 for receiving the hooked end 48 of one part of connecting rod 21. The cover 34 may also be provided with an aperture 49 permitting free passage of air from the interior of the sylphon 24.

90 The pressure chamber 30 may be provided with one or more apertures 50 leading to a bore 51, which is independently threaded at 52 for receiving a fitting 53 adapted to be secured to the conventional metal pipe 25

by means of the internally threaded sleeve 55. The metal pipe 25 is connected to the oil pump 26 to transmit pressure from the pump 26 when the pump is actuated by the engine.

The plunger 37 may comprise a metal member having an upper cylindrical portion 54 adapted to be slidably received in the bore 40 of cover 34. At its opposite end the plunger 37 is provided with flat sides 56 forming shoulders 57 against which the bottom plate 36 of sylphon 24 may be secured by soldering or other convenient fastening means. The flattened portion 56 of plunger 37 is adapted 15 to be slidably received in a complementary aperture 58 formed in a lug 59 carried by the interior of the casing and substantially aligned with the center of the bore 40, forming a second guide member for plunger 37.

The lower end 60 of the plunger 37 may be beveled to prevent interference with other parts of the mechanism, and to cam the mechanism back into proper position when the plunger is moved into the position of Fig. 2.

The plunger 37 is also provided with a transverse groove 61 which may be of substantially circular cross-section and formed with rounded edges for permitting the plunger 37 to cam out a pawl 62, further to be described. The pawl 62 may comprise a metal member formed with one or two laterally projecting arms 63 having curved end surfaces 64 which are complementary to the groove 61, and having a weight 65 located 25 on the opposite side from the apertures 66 which receive a pin for pivotally supporting pawl 62 on lever 67. The arms 63 and 64 are separated by a slot 68, the base of which is indicated at its top in Fig. 6 as a 30 stop member 69, and the lower part of the weight 65, adjacent slot 68, constitutes a second stop member indicated by numeral 70.

The pawl 62 is pivotally mounted upon a lever 67 with the base of the slot 68 sufficiently spaced from lever 67 to permit a slight lost motion between the pawl and lever, the amount of lost motion being determined by the relative positions of the stop surfaces 69 and 70. The lever 67 comprises a member which is adapted to extend longitudinally of the casing 29 and which is pivotally supported within casing 29 upon an inwardly projecting lug 71 by a pin 72. The upper end of lever 67 pivotally supports the pawl 55 62 while the lower end may be curved to correspond to the adjacent wall of casing 29, and adapted to extend into the metallic solid 27 which is adapted to melt at a predetermined temperature.

In order to reduce the amount of the alloy 27, the casing 29 may be reduced in size at its lower end, forming a relatively small metal chamber 73, of sufficient size to receive the lower end of plunger 37 when the parts 60 65 are in the position of Fig. 2, and to permit

the necessary pivotal movement of lever 67 when the parts are in the position of Fig. 3. The exterior surface of the lower end 74 of casing 29 may be cylindrical and provided with a threaded portion 75 of reduced size, adapted to be received in a threaded bore 76 in the engine block 77, or in a similar bore 78 in a metal fitting 79 having an aperture 80 for receiving one of the stud bolts 81 with which the engine block 77 is provided. The fitting 79 is thus adapted to permit the attachment of the shutter controlling device to an engine block by means of the usual bolts without forming and threading a new bore.

It will thus be observed that the present device is adapted to be secured in heat conducting relation with a part of the internal combustion engine, so that heat is conducted through the metallic parts of the casing 29 to the metallic alloy 27, which melts at a predetermined temperature. The operation of the present invention is as follows: When the engine is cold and the motor is not running, the parts are in the position shown in Figs. 90 1 and 2, the shutters 14 being maintained closed by the spring 19 and the plunger 37 being latched in the position of Fig. 2 by the pawl 62, which is in turn secured by engagement of the stop surface 70 with lever 67, 95 the lower end of which is secured in the frozen solid 27.

When the motor is started the pressure generated in the oil pump 26 is transmitted by means of conduit 25 and the oil contained 100 in the conduit 25 and chamber 30, to the bellows 24, but outward movement of the plunger 37 is prevented by the pawl 62, and consequently, the oil pressure is ineffective to open the shutters until the engine has reached 105 a predetermined temperature.

When the engine has reached the predetermined temperature at which the alloy 27 melts, the melting of the alloy 27 will permit the lever 67 to pivot in a clockwise direction, 110 and this pivotal movement will be aided by the upward thrust of the oil on sylphon 24 and its bottom plate 36.

The oil pressure in the chamber 30 will then be effective to move the plunger 37 upward, the pawl 62 moving with plunger 37 until the parts reach the position of Fig. 3 when continued motion of plunger 37 cams pawl 62 outward and moves the lever 67 to the position of Fig. 3.

The weight 65 provided at the right hand side of the pawl 62 tends to urge the pawl 62 into engagement with the plunger 37 and the weight of the lever 67 which is pivoted at a point on one side of its center of gravity, 120 causes the lever 67 to tend to return to the position of Figs. 2 and 4.

Consequently, the plunger 37 passes from the position of Fig. 3 to that of Fig. 4, rotating bell crank 23 counterclockwise, bell crank 125 130

20 counterclockwise and moving shutter bar 18 downward to open shutters 14. The lever 67 and pawl 62, however, move to the position shown in Fig. 4, the lever 67 taking substantially the same position as in Fig. 2. The weight of the lever 67 being greater than the weight 65 on the pawl 62, the motion of the lever 67 to the position of Fig. 4 tends to move the pawl against the plunger 37, so that the stop surface 70 is spaced from lever 67 while stop surface 69 engages lever 67.

It will thus be observed that the lever 67 has returned to its initial position, so that if the engine should cool down while running, the solid 27 will freeze with the lever 67 in the proper position, and the pawl 62 is also urged into engagement with the plunger 37 at such an angle that when the plunger 37 returns to the position of Fig. 2, the pawl will naturally be drawn into the groove 61 to retain the plunger in the position of Fig. 2.

If the engine should cool during the running of the motor by reason of unusually cold weather, the mechanism of the control device will be maintained in the proper position for the next operation, and the thermal solid will freeze with the parts in the initial position.

When the motor is stopped, the shutters will close at once due to the cessation of oil pressure generated by pump 26 and practically all of the heat will be kept within the internally combustion engine to keep the engine warm for the next starting operation. When the motor is again started the same cycle of events will be repeated.

It will thus be observed that the present device is adapted to close the shutters as soon as the engine stops and shutters constructed according to the present invention are also adapted to be opened at a temperature which may be very accurately predetermined since it depends upon the melting point of a metallic solid.

The present device is also simple and the thermal control cannot change its characteristics even after a long period of use.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim is new and desire to secure by Letters Patent of the United States is:

1. In a shutter control for regulating the flow of air about internal combustion engines, the combination of an enclosure with shutters for controlling flow of air about an engine part, actuating means responsive to the running condition of the engine to actuate said shutters, and means released by

the melting of a metallic solid responsive to heat from said engine for controlling said actuating means.

2. In a shutter control for regulating the flow of air about internal combustion engines, the combination of an enclosure with shutters for controlling flow of air about an engine part, actuating means responsive to the running condition of the engine to actuate said shutters, and a latching device held by a metallic solid adapted to be melted at a predetermined engine temperature.

3. In a shutter control for regulating the flow of air about internal combustion engines, the combination of an enclosure with shutters for controlling flow of air about an engine part, actuating means responsive to the running condition of the engine to actuate said shutters, and a latching device held by a metallic solid adapted to be melted at a predetermined engine temperature, comprising a member secured by said solid and a pawl adapted to permit said member to return to its initial position after an unlatching operation.

4. In a shutter control for internal combustion engines, the combination of a plurality of shutters with a pressure responsive device actuated by oil pressure for actuating said shutters, releasable securing means for rendering said pressure responsive device inoperative, and a solidified metallic substance adapted to release said securing means when a predetermined engine temperature is reached.

5. In a shutter control for internal combustion engines, the combination of a plurality of shutters with a pressure responsive device actuated by oil pressure for actuating said shutters, a pawl for securing said pressure device in inoperative position and a member secured in a metallic solid adapted to melt at predetermined engine temperature, for supporting said pawl.

6. In a shutter control for internal combustion engines, the combination of a plurality of shutters with a pressure responsive device actuated by oil pressure for actuating said shutters, a pawl for securing said pressure device in inoperative position and a member secured in a solid adapted to melt at predetermined engine temperature, for supporting said pawl, said member being adapted to return to its initial position after melting of said solid.

7. In a shutter control, the combination of a plurality of shutters with a thermal control comprising a metallic solid adapted to be melted at predetermined engine temperature, and an element for controlling said shutters, said element being secured by said solid and adapted to be released by the melting thereof.

8. In a shutter control, the combination of a plurality of shutters with a thermal con-

trol comprising a metallic solid adapted to be melted at predetermined engine temperature, an element for controlling said shutters, said element being secured by said solid and adapted to be released by the melting thereof, and a lost motion connection between said element and said shutters whereby said element may return to its initial position after melting of said solid for securing the same again on freezing of said solid.

9. In a shutter control, the combination of a casing with a pressure responsive member carried by said casing, a movable member for actuating shutters, a metallic solid adapted to melt at a predetermined temperature, in said casing, and a latching device adapted to secure said member in a predetermined position.

10. In a shutter control, the combination of a casing with a pressure responsive member carried by said casing, a movable member for actuating shutters, a metallic solid adapted to melt at a predetermined temperature, in said casing, and a latching device adapted to secure said member in a predetermined position, comprising a lever and a pawl, said lever being releasably secured by said solid.

11. In a shutter control, the combination of a casing with a pressure responsive member carried by said casing, a movable member for actuating shutters, a solid adapted to melt at a predetermined temperature, in said casing, and a latching device adapted to secure said member in a predetermined position, comprising a lever, a pawl, said lever being releasably secured by said solid, and a lost motion connection between said pawl and lever.

12. In an engine shutter control, the combination of a casing with an expansible member carried by said casing, a plunger slidably mounted in said casing, and adapted to be moved by said expansible member, and a solid adapted to be melted at a predetermined engine temperature, for preventing movement of said plunger.

13. In an engine shutter control, the combination of a casing with an expansible member carried by said casing, a plunger slidably mounted in said casing, and adapted to be moved by said expansible member, a solid adapted to be melted at a predetermined engine temperature, for preventing movement of said plunger, a lever pivoted in said casing and having a part secured in said solid, and means carried by said lever for engaging said plunger.

14. In an engine shutter control, the combination of a casing with an expansible member carried by said casing, a plunger slidably mounted in said casing, and adapted to be moved by said expansible member, a solid adapted to be melted at a predetermined engine temperature, for preventing movement of said plunger, a lever pivoted in said casing

and having a part secured in said solid, and means carried by said lever for engaging said plunger, comprising a pawl having a lost motion connection to said lever to permit return of said lever after releasing said plunger.

15. In an engine shutter control, the combination of a casing, metal bellows within the casing communicating with the exterior thereof and subject to compression by pressure within the casing, means for supplying fluid under pressure to said casing when the engine is running, and means including a low melting substance for preventing compression of the bellows until heat from the engine melts said substance.

16. In an engine shutter control, the combination of a metal bellows, means operated by the engine when running adapted to compress the bellows, latch means adapted to prevent the compression of the bellows, and a fusible substance adapted to be melted by heat from the engine and adapted to provide a temporary abutment for holding the latch in operative position.

17. In an engine shutter control, the combination of a metal bellows, means operated by an engine when running adapted to move the bellows to operate the shutters, latch means adapted to prevent such movement of the shutter, and a fusible substance adapted to be melted by heat from the engine and adapted to provide a temporary abutment for holding the latch in operative position.

In witness whereof, I hereunto subscribe my name this 25th day of March, 1929.

FREDERICK C. BARGAR.
